UNITED STATES PATENT OFFICE.

RICHARD G. INWOOD, DECEASED, LATE OF SOUTH BEND, INDIANA, BY MARY CAIN INWOOD, ADMINISTRATRIX, OF SOUTH BEND, INDIANA, ASSIGNEE TO WIRE-BOUNDS PATENTS COMPANY, OF KITTERY, MAINE, A CORPORATION OF MAINE.

BOX-MAKING MACHINE.

1,371,487.

Specification of Letters Patent. Patented Mar. 15, 1921.

Application filed January 10, 1916. Serial No. 311,263.

To all whom it may concern:

Be it known that RICHARD G. INWOOD, deceased, late a citizen of the United States, and resident of South Bend, in the county 5 of St. Joseph and State of Indiana, has invented an Improvement in Box-Making Machines, of which the following is a specification.

This invention relates to the class of machines used in making wirebound boxes, box blanks or parts, and the purpose thereof is 10 to provide a machine which will position box fastenings as desired. For example, in manufacturing wirebound box blanks it is 15 desirable to space the staples which secure the wire to the side material and cleats so as to avoid driving staples between the several sections of a blank and between succeeding blanks, and also to place the staples in a 20 predetermined relation to the edges of each section.

The invention will be best understood by reference to the following description of 25 one illustrative embodiment thereof, taken in connection with the accompanying drawings, wherein:—

Figure 1 is a side elevation of a portion of a machine embodying the invention;

Fig. 1^a is a section on line 1^a—1^a of Fig. 1; 30 Fig. 2 is a side view partly in elevation and partly in section, the operating parts being in a phase different from that of Fig. 1;

Fig. 3 is an end elevation seen from the 35 left of Fig. 1;

Fig. 4 is an elevation of a part of the conveyer chain, the supporting guide appearing in section;

Fig. 5 is a plan of part of the conveyer 40 chain;

Fig. 6 is a section on line 6—6 of Fig. 4;

Fig. 7 is a side elevation of one end of the pawl positioning link;

Fig. 8 is an end elevation thereof;

Fig. 9 is a view in plan showing a portion 45 of the ratchet wheel and the levers and link which coöperate therewith; and

Fig. 10 is a section on line 10—10 of Fig. 9.

Referring to Figs. 1 and 3, an embodiment 50 of the invention is illustrated as applied to a wirebound box-blank machine of known type, and embodying the stapler

head 3 reciprocated by any suitable means, such as the pitman and eccentric 5, and carrying staplers, shown diagrammatically in Fig. 3 and indicated by the reference numeral 7, for operating upon box material which is fed beneath the stapler head by suitable carrier mechanism. This carrier 60 mechanism in the present instance comprises suitable carrier chains 9, two or more of which are provided, and which are trained over the sheaves 11. These sheaves are preferably adjustable to vary the distance 65 between them, so as to accommodate different sizes of blanks, and the carrier chains are made channel shaped, as seen in Figs. 3 and 1^a, to accommodate box cleats in the well known manner. Abutments 13 may be provided 70 between the chains to clench the staples which secure wires to the side material between the lateral cleats.

The sheaves are given a step-by-step movement alternating with the reciprocations of the stapler head 3 to feed the conveyer chain and with it the blank material. In the present application, is shown a suitable mechanism whereby the length of these feeding steps may be suitably varied so as 80 to position the staples driven by the stapler head 3 at any desired intervals.

To impart feeding movement to the sheaves and chains, the shaft 15 carrying the sheaves is intermittently rotated by a 85 suitable mechanism, herein exemplified by the ratchet wheel 17 coöoperating with a driving pawl 19. It will be understood, however, that any equivalent intermittent gripping device may be utilized and that 90 reference herein to a ratchet wheel and pawl is in an exemplary sense. The pawl 19 is carried between two levers 21 and 23, pivoted at the axis of ratchet wheel 17 at the outside and inside thereof respectively. To 95 impart a driving stroke to the pawl, an actuating lever 25 is provided, pivoted at the axis of wheel 17 and connected to the eccentric 27 on the main driving shaft, which will give the same an oscillating or reciprocating motion. One end of lever 25 extends partially beyond the axis, and is provided with a lug 29 which is arranged to contact with the pin 31 on the pawl-carrying lever 21. Described differently, it may be said 100 that the actuating lever 25 and the pawl 105

carrying lever are connected by a rule joint, that is, a joint which may be broken in but one direction.

In Fig. 2 are shown the parts as they would be with the eccentric at one extreme of its throw and the actuating lever carried to the limit of its driving stroke, carrying with it the pawl-carrying lever and advancing the wheel. On the return stroke, the 5 spring 33, attached to lever 21 and to any suitable point on the frame of the machine, will normally maintain the pin 31 in contact with lug 29, and the pawl carrying member will be carried back as far as the actuating 10 lever 25. The rule joint provided by the parts 29 and 31, however, affords opportunity for lost motion between the two levers, and if the lever 21 is checked in its rearward movement against the force of the 15 spring, the lever 25 will move to the end of its stroke alone, as shown in Fig. 1, and on its return will pick up, as it were, the lever 21 at an intermediate point in the stroke, and the working or driving stroke of 20 the pawl-carrying member will be correspondingly shorter.

Suitable means are provided for limiting the return movement of the pawl-carrying lever 21 to regulate the amount of its working stroke. In the present instance, a plurality of stop members are provided which are arranged for a successive presentation correlated with the movement of the conveyer means, and suitable means are provided 30 coöperating with such stop members to render them effective to check the back movement of the pawl-carrying lever 21. In the embodiment of the invention here shown, the stop members are associated with 35 the conveyer itself and successively brought forward by it in its movement. For this purpose, the conveyer chains may be constructed as shown in detail in Figs. 4, 5 and 6. As there shown, each link of the chain 40 9 is of channel construction, supported on the channeled guide 35 which forms part of the frame of the machine. Suitable spacing blocks 37 are used to properly position the cleats of the box blank in the channels in 45 the manner well understood. One flange of the channel, herein the outer flange, may be provided with a reinforcing rim or flange 39 in which are formed holes 41, which afford means for selective positioning of 50 stop members 43. The stop members may be screws adapted to be tapped into the holes 41. Connected to the pawl-carrying lever 21 is a link 45, having at its other end a head 47 adapted to contact with the screws 55 43 or stops 43 on the conveyer chain. Referring particularly to Fig. 2, it will be understood that when the pawl lever 21 is released from the driving action of the actuating lever 25 and moves backward therewith under the

influence of the spring 33, the head 47 may 65 come in contact with a stop pin 43 on the conveyer chain, and that the movement of the lever 21 will thereby be checked, the rule joint at 29—31 be broken, and lost motion between the fixed throw actuating 70 lever 25 and the pawl lever be provided for. The next feeding movement imparted to the ratchet wheel will, therefore, be correspondingly shorter than that which would be effected by the full stroke of the eccentric 27. 75

The head 47 of link 45 is provided with the beveled extension 49 adapted to coöperate with the beveled face 51 of a block 53, secured in any suitable manner to the frame of the machine. A spring-pressed keeper 80 55 is provided to hold the link 45 down to the block 53. Referring to Fig. 1, as the lever moves to the left in its stroke, it is apparent that the face 49 will ride up the face 51 against the force of spring 55, lifting 85 the head 47 to the top of block 53 and disengaging it from the stop 43, while the conveyer continues to move forward to the full extent imparted by the pawl-carrying lever 21 to the position shown in Fig. 2. On the 90 return stroke, the link 45 will be carried to the right with the pawl-carrying lever, and the head will drop down from the block into position to engage another stop on the conveyer chain. It will be obvious that, by a 95 suitable spacing of the stop pins on the chains, a series of steps, each of any desired length within the maximum provided for by the throw of the actuating lever 25, may be effected.

In the specific machine illustrated herein, the links of the conveyer chain are of considerable length, and to suit this arrangement the sheaves 11 are made in polygonal form with their sides appropriately proportioned to the chain links. As the sheaves turn and feed the conveyer chain, it is evident that the effective crank arm of the sheave acting on the chain varies according as one of the vertices or one of the sides of 110 the polygon is uppermost. When one of the sides is uppermost, thereafter in the movement of the sheaves, as the adjacent vertex approaches a position vertically above the axis of movement, the effective crank arm 115 of the sheave will increase and thereby cause the chain to travel at increased speed. As this same vertex moves from its position above the axis of movement toward the left, the chain speed will decrease until it reaches 120 its minimum, when the side of the polygon stands uppermost. Since the specific staple placing mechanism shown in the drawings operates under the control of stops on the chain, it is apparent that these variations in 125 chain speed might well produce some slight variations in staple placing, and while these variations, in many cases, would be negligi-

ble, the present apparatus embodies means approximately to compensate for such variations.

The illustrative compensating mechanism 5 is shown in Figs. 1, 2, 3, 9 and 10. The link 45 has at its left-hand end a pin 57, having a head 59, sliding in longitudinal guideways 61 on the lever 23, so that the point of connection between the link 45, and the lever 23 10 which reciprocates it, can be moved to different radial distances from the axis of movement of the lever 23—in other words, so that the lever arm by which the link 45 is reciprocated may be varied in length. To produce this variation in length of lever arm, 15 the link 45 is provided with a roller 63 (see Fig. 10) which is arranged to ride on the flanges 39 of the links of chain 13, as shown in Fig. 3. In the rotation of the polygonal 20 sheave, as one of the vertices of the polygon approaches its uppermost position, the chain is thereby lifted and correspondingly lifts the roller 63 and the link 45. The spring 55 serves to hold down the right-hand end of 25 the link 45 so that in the described lifting movement, it fulcrums on the block 53. Thus the lifting of the roll 63 slides the head 59 outwardly in the guide 61 and thereby increases the length of the lever arm (of the 30 lever 23) by which the link 45 is reciprocated. The operation just described takes place during a contraclockwise movement of the lever 23, so that when the lever comes to rest, leaving the polygonal sheave at rest 35 with one of its vertices uppermost, or approximately uppermost, the lever arm, effective to return the link 45 toward the right in Fig. 2, has been elongated slightly. Therefore, a greater extent of movement to- 40 ward the right is effected, and this tends to compensate more or less for the fact that the immediately preceding feed step of the conveyer has advanced the stop 43 slightly more than the normal feed step.

45 Where the variations in staple placing occasioned by the polygonal form of the sheaves are considered negligible, it is unnecessary to provide the adjustable connection of the link 45 to the lever 23 through 50 the pin 57 and head 59; and the two may be connected simply by a fixed pivot or in any suitable manner as will appear to those skilled in the art.

While in considerable detail the embodiment of this invention illustrated in the accompanying drawings, and the various mechanisms utilized in the machine shown have been fully described, it will be understood that this has been done with a descriptive 55 rather than with a defining intent, in order that the operation of the embodiment chosen as an example of the invention might be more quickly comprehended, and not because the exact mechanisms shown are essential.

Having described the invention, what is claimed is—

1. A machine of the class described comprising, in combination, a conveyer for the box materials, means for intermittently advancing the same comprising a ratchet wheel, a pawl-carrying member, an actuating lever and means for oscillating the same, said lever having driving engagement with said member on movement in one direction and provision for lost motion relatively thereto on movement in the other direction, the stop members arranged for a successive presentation correlated with the movement of said conveyer to check movement of said pawl-carrying member in said other direction. 70

2. A machine of the class described comprising, in combination, a conveyer for the box materials, means for intermittently advancing the same comprising a ratchet wheel, a pawl-carrying lever and an actuating lever and means for oscillating the latter, means connecting said levers to permit the latter to drive the former embodying a rule-like joint breakable in but one direction, 85 means for normally maintaining said joint unbroken, and means including stop members arranged for a successive presentation correlated with the movement of said conveyer for breaking said joint to permit lost motion between said levers whereby the feed of the ratchet is varied. 90

3. A machine of the class described comprising, in combination, a conveyer for the box materials, means for intermittently advancing the same comprising a ratchet wheel, an actuating lever and a pawl-carrying lever pivoted concentric with said wheel, a lug on the latter and an extension on the former engaging the lug at the rear side thereof, a spring to hold said lug in contact with said extension, stop members arranged for a successive presentation correlated with the movement of said conveyer and means coöperating with said stop members for checking said pawl-carrying member in its rearward movement. 100

4. A machine of the class described comprising, in combination, an endless conveyer for the box materials, polygonal sheaves carrying the same and driving means including an oscillating driving member having means for applying force to rotate the sheaves in one direction of movement, a fixed throw actuating member therefor, there being provision for lost motion between said actuating member and driving member whereby to vary the effective stroke of the latter, means on the conveyer for regulating said lost motion and means associated therewith for compensating for the irregular movement due to said sheaves. 115

5. A machine of the class described comprising, in combination, an endless conveyer for the box materials, means for intermit- 120

tently advancing said conveyer, mechanism 43, 45 regulating the action of said advancing means and a device 63 automatically modifying the effect of such mechanism in 5 compensation for variations in transmission of movement from said advancing means to said conveyer.

6. A machine of the class described comprising in combination, an endless conveyer 10 for the box materials, polygonal sheaves carrying the same, a ratchet on a sheave, a pawl-carrying lever, an actuating member therefor, there being provision for lost motion between said actuating member and 15 pawl-carrying lever, mechanism including a plurality of stop members arranged for a successive presentation correlated with the movement of said conveyer, link-work co-operating with said stops to check movement 20 of said pawl-carrying lever with said actuating member and means governed by the effective crank arm length of said driving sheaves to modify the action of such link-work on said lever.

25 7. A machine of the class described comprising, in combination, an endless conveyer for the box materials, polygonal sheaves carrying the same, a ratchet on a sheave, a pawl-carrying lever, an actuating member 30 therefor, there being provision for lost motion between said actuating member and pawl-carrying lever, mechanism including a plurality of stop members arranged for a successive presentation correlated with the 35 movement of said conveyer, a link arranged to slide along said lever and co-operating with said stops to check movement thereof with said actuating member and means on said link bearing on the conveyer for sliding 40 the former on said lever as the conveyer tightens and slackens under action of said sheave.

8. A machine of the class described comprising, in combination, an endless conveyer 45 for the box materials, polygonal sheaves carrying the same, a ratchet on a sheave, a pawl-carrying lever, an actuating member therefor, there being provision for lost motion, between said actuating member and 50 pawl-carrying lever, stops on said conveyer, a link sliding on said pawl-carrying lever and arranged to extend into the path of said stops, an extension on said link bearing on said conveyer whereby to slide the link on 55 said lever as the conveyer tightens and slackens.

9. A machine of the class described comprising, in combination, a conveyer for box materials, stapling mechanism, means for 60 intermittently advancing said conveyer to present portions of the box material to the stapling mechanism comprising a ratchet, a pawl-carrying lever, an actuating lever, means for oscillating the latter and a connection between said levers to permit the 65

latter to drive the former embodying a rule-like joint breakable in but one direction, means for normally maintaining said joint unbroken and means for breaking said joint at predetermined points in the travel of the 70 actuating lever to give feeding movements of varied predetermined lengths to the box materials.

10. A machine of the class described comprising in combination, a stapler head and 75 means for feeding blank materials step by step beneath the same including, in combination, an oscillating member adapted to impart motion to the materials on movement in one direction, a fixed throw actuator, a connection between said member and actuator embodying a rule-like joint breakable in but one direction, means for maintaining 80 said joint normally unbroken, stop members arranged for a successive presentation correlated with feeding movement of the blank material and means for rendering 85 said members effective for breaking said joint to permit lost motion between said oscillating member and actuator. 90

11. A machine of the class described comprising, in combination, a stapling mechanism and a work holder and means for moving one intermittently relatively to the other, said means comprising an oscillating member adapted to impart motion on movement in one direction, an actuator, a connection between said member and actuator embodying a rule-like joint breakable in but one direction, means for maintaining 95 said joint normally unbroken, and means rendered effective at times dependent on the relative positions of said stapling mechanism and work holder for breaking said joint to permit lost motion between said 100 oscillating member and actuator. 105

12. A machine of the class described comprising, in combination, a stapler head and means for feeding blank materials step by 110 step beneath the same including, in combination, an oscillating member adapted to impart motion to the materials on movement in one direction, a fixed throw actuator, a connection between said member and actuator embodying a rule-like joint breakable in but one direction, means for maintaining 115 said joint normally unbroken, and means rendered effective at times dependent on the position of said blank materials relative to the stapler for breaking said 120 joint to permit lost motion between said oscillating member and actuator.

13. A machine of the class described comprising, in combination, fastener-setting mechanism; work-supporting means; and 125 means to cause relative progression between work and fastener-setting mechanism in controlled intervals to position fasteners as desired, including a set of controlling members acting successively in correlation with 130

the progression, and means modifying the controlling effect of said members to compensate for irregularity in rate of progression.

5 14. A machine of the class described comprising, in combination, fastener - setting mechanism; work-supporting means; and means to cause relative progression between work and fastener-setting mechanism in controlled intervals to position fasteners as desired, including pattern means and co-operating means to cause such intervals of progression as determined by the pattern means, and means modifying the action of 10 said pattern means to compensate for irregularity in action of the machine.

15. A machine of the class described, comprising, in combination, fastener - setting mechanism; work-supporting means; and 20 means to cause relative progression between work and fastener - setting mechanism in controlled intervals to position fasteners as desired, including a set of controlling members successively presented in correlation 25 with the progression, means successively controlled thereby to impart motion, and means for modifying the control to compensate for irregularity of progression.

16. A machine of the class described comprising, in combination, fastener - setting mechanism; work-supporting means; and means to cause relative progression between work and fastener-setting mechanism in controlled intervals to position fasteners as 35 desired, comprising actuating and transmission means, a set of controlling members successively presented in correlation with the progression to control intervals of progression, and means to modify the control 40 to compensate for irregularity of progression.

17. A machine of the class described comprising, in combination, fastener - setting mechanism; work-supporting means; and 45 means to cause relative progression between work and fastener-setting mechanism in controlled intervals to position fasteners as desired, comprising actuating and transmission means, means for controlling the 50 transmission means in accordance with the progression, and means for modifying the effect of the latter to compensate for irregularities of progression.

18. A machine of the class described comprising, in combination, means for moving the work, fastener-setting mechanism, means for controllably positioning fasteners on the work successively controlled by positions of the latter relative to the fastener - setting 60 mechanism, and means for modifying the action of said last-named means to compensate for irregularity in the movement of the work.

19. A machine of the class described comprising, in combination, means for moving

the work, fastener-setting mechanism, and means for controllably positioning fasteners on the work including controlling members moving in unison with the work and means to correct their control to compensate for 70 irregularity of movement.

20. A machine of the class described comprising, in combination, fastener - setting mechanism, work - supporting means, and feed-mechanism to cause relative movements 75 between the work and fastener-setting mechanism, said feed mechanism comprising controlling members successively presented in correlation with feed movements, means successively controlled thereby for imparting 80 feed movements, and correcting means to compensate for irregularity of feed movements.

21. A machine of the class described comprising, in combination, mechanism to secure binding wire to box parts; a conveyer for presenting the work thereto; conveyer-controlled means regulating the feed for effecting a desired position of fasteners on the work; and means modifying the action 90 of said last named means to compensate for irregularities of feed.

22. A machine of the class described comprising, in combination, mechanism to secure binding wire to box materials, a step- 95 by-step fed conveyer for said materials; and conveyer-controlled means, including correcting means to compensate for irregular movement of the conveyer, regulating the feed for effecting a desired disposition of 100 fasteners on the work.

23. A machine of the class described comprising, in combination, driven - means for moving the work; means to secure binding wire to the work; means for operating said driven means including a set of successively presented controlling members and means for modifying the action of the latter to compensate for irregularities of movement. 105

24. A box blank machine comprising, in combination, coöperating blank feeding and binding wire applying mechanism constructed and arranged to provide a continuously operating organization for wiring successive blanks; said organization including automatic means controlling the feed for controllably locating individual fasteners of the respective blanks, and automatic correcting means therefor. 110

25. The combination of fastener-setting 120 mechanism; work-supporting means; and means for relatively moving work and fastener - setting mechanism comprising a ratchet wheel and pawl-carrying member; an actuating lever having driving engagement with said member on movement in one direction and arranged for lost motion relatively thereto on movement in the other direction; and stop members successively presented in correlation with relative move- 125 130

- ments to check movement of said pawl-carrying member in said other direction.
26. In a machine of the class described the combination with fastener-setting mechanism of means to cause step-by-step movements between said mechanism and the work, comprising a ratchet wheel and a pawl-carrying lever; an actuating lever having a joint with said pawl-carrying lever breakable in but one direction; and automatic means controlling the breaking of said joint.
27. In a machine of the class described the combination with fastener-setting mechanism of means to cause step-by-step movements between said mechanism and the work, comprising a ratchet wheel and a pawl-carrying lever; an actuating lever having a joint with said pawl-carrying lever breakable in but one direction; and stop members successively presented in correlation with step movements to limit movement of the pawl-carrying lever in the direction in which the joint is capable of breaking.
28. The combination of fastener-setting mechanism; work-supporting means; a ratchet feed mechanism including a pawl-carrying lever; an actuating lever adapted during different phases of its movement in one direction to engage and move the pawl-carrying lever; a spring for returning said pawl-carrying lever; and automatic means for determining the period of engagement of said actuating lever with the pawl-carrying lever.
29. A machine for use in making boxes comprising, in combination, a work support; fastener-setting mechanism; means to cause relative progression between said mechanism and the work, including controlling means to locate fasteners at selected points in the work; and automatic correcting means for said controlling means.
30. A machine for use in making boxes comprising, in combination, a work support; fastener-setting mechanism; means to cause relative progression between said mechanism and the work, including controlling means to locate fasteners at selected points in the work; and means to render said controlling means effective to locate fasteners at the selected points regardless of irregularity of progression.
31. A machine for use in making boxes comprising, in combination, a work support; fastener-setting mechanism; means to cause relative progression between said mechanism and the work; means to control said relative progression to locate said fasteners at desired points in the work; and means to render said controlling means effective regardless of irregularity of progression.
32. A machine for use in making wire-bound boxes comprising, in combination, means including fastener-setting mechanism for applying binding wire to box parts; means to cause relative progression between said mechanism and the work; means automatically controlling the progression to locate individual fasteners; and a correcting device for said last named means.
- In testimony whereof, I have signed my name to this specification.
